UNITED STATES PATENT OFFICE.

HAROLD F. PARISH, OF BROOKLYN, NEW YORK, ASSIGNOR TO GRINDEN ART METAL COMPANY, OF BROOKLYN, NEW YORK, A CORPORATION OF NEW YORK.

METALLIC STRUCTURE, SUCH AS DOORS AND THE LIKE.

1,086,934.

Specification of Letters Patent.

Patented Feb. 10, 1914.

Application filed May 20, 1912. Serial No. 698,503.

To all whom it may concern:

Be it known that I, HAROLD F. PARISH, a citizen of the United States of America, and residing in the borough of Brooklyn, in the 5 county of Kings and State of New York, have invented a certain new and Improved Metallic Structure, Such as Doors and the like, of which the following is a specification.

10 My invention relates to metallic structures such as doors, partitions, frames and windows and the object thereof is to produce a metallic structure of improved artistic appearance which can be economically 15 manufactured and which shall be light and at the same time strong.

Further objects of my invention will be hereinafter referred to in the following detailed description of the invention.

20 In the accompanying drawings, the invention is illustrated in a metallic door, but it is to be understood that, except as specifically pointed out, the invention is susceptible of modification without departing from the 25 spirit of my invention and it is equally applicable to structures other than doors.

Figure 1 is an elevation of a door embodying my invention; Fig. 2 is a broken section thereof on the line 2—2, Fig. 1 drawn to a 30 larger scale; and Figs. 3 to 8 are sections of modified details.

The structure illustrated is a door of the type in which the frame members, viz., the stiles 10 and 11 and cross rails 12, 13 and 14 35 of each face of the door, are integral and the door frame is completed by suitably securing together these two opposite faces A—B at the edges of the door. Where panels 15 and 16 are employed as illustrated, these are 40 independent from the frame members and are held in position upon the frame by suitable securing means. The structure is thus distinct from the type of the door in which the stiles and rails are separate, being formed 45 of independent frame elements in which both faces of the door are combined by a channeled construction. It is also distinct from the type in which not only the frame for each face of the door is integral, but the 50 panels are also integral with the frame, being raised or depressed as may be desired. The problems to be faced in the construction of these types of doors are quite different, and a solution for one is by no means a solution for the other. While the manner of se-

curing together the two door faces may be varied in many ways, I prefer to effect this, for the top rail and stiles, by bending over at right angles and for an equal distance from each face their respective margins 17, 30 the edges of which are recurved to form open channels 18. The bottoms of the latter, in assembled condition, are thus juxtaposed on a line midway between the two door faces. To unite these edges and at the 35 same time to stiffen and strengthen the door, I provide a stiffening bar 19 extending as a strut member between the inner faces of the two sheets A and B and having its edges recurved to engage and interlock with the 40 channels 18. The parts may now be electrically welded or riveted together, preferably the former, as giving the more finished appearance. It will be observed that in this condition the edges of the door are closed on 45 three sides, while the bottom edge is left open for the purpose of perfecting the joint at the edge of the lower panel as will be hereinafter explained.

Presuming that the upper panel 15 to be 50 inserted in the registering apertures of the door is to be a pane of glass, the edges of the plates A and B at the glass aperture are cut on the miter at the corners and the edges are folded inward to form 55 an open channel 21 and then recurved to form a second and parallel channel 22 oppositely faced. A molding 23 with glass supporting ledge 24 spans the space between faces A and B, and its edges are inserted in the opposite channels 22. A stiffening bar 25 is also spaced between the plates A and B with the side flanges of the bar inserted in the opposite channels 21. After the glass 15 is in position, a retaining 60 molding 26, one edge of which enters the channel 22, is pressed against the face of the glass and is drawn into snug engagement therewith by screws 27 which enter threaded holes in the reinforcing bar 28 welded or 65 otherwise secured to one face of the supporting ledge 24.

The advantage of the construction shown is obvious, since it permits the ready removal of the molding 26 for the insertion of a 70 panel of glass. If this panel is made of non-breakable material so that replacement is not likely to be necessary, the construction employed for the lower panel is preferred.

At the lower panel opening the edges of 75

the apertures are folded on three sides to form two parallel oppositely faced channels 29 and 30 as in the upper panel opening, while the fourth side, viz., the bottom in the 5 construction shown, is folded in one direction only, to form the single channel 31. For a one piece panel 16, as shown in Fig. 2, a panel supporting molding 33 with panel receiving slideway 34 is spanned between 10 the channels 30 on three sides. At the bottom of the panel the construction must be different in order to permit the insertion of the panel which is slid through the bottom of the door into the depression 34 of the side 15 and top molding 33. A following and supporting molding 35 engages the lower edge of the panel and is in turn held in position by the stiffening bar 36, the channels 37 of which receive the edges of the molding and 20 the inner edges of the opposite channels 31. The parts are secured together in any suitable way, preferably by welding.

The bottom of the door, which has been left open for the insertion therethrough of 25 the panel 16, molding 35 and stiffening bar 36, is closed by an inverted stiffening bar 38, the edges of which are turned down and welded in the channels 39 formed by the upturned edges 40 of the bottom margins 30 of the side plates A and B. A recess 41 is thus afforded for the reception of weather stripping or other material which it may be desired to arrange at the bottom of the door.

35 The manner of constructing and assembling the door is readily understood and may be varied in many ways. For example, the blank of sheet metal is first formed with the central apertures for the panels, and the 40 margins of the panel apertures and of the sheet as a whole then folded to form the edges of the door and the inturned keyways or channels. At the corners of the door the metal is unavoidably cut away slightly to 45 afford clearance for the folding dies, and sufficient room is thus afforded at the top of the vertical edges for the passage of the flat reinforcing key bar 19 through the clearance space at the corner into engagement with the channels 18. This corner seam is in any event unavoidable, by reason 50 of the fact that the margins of the sheets are folded over, both at the top and at the sides of the door, and the insertion of the 55 key 19 aids in filling the seam which is closed by a line of solder, or electrical welding in accordance with the process disclosed in my Patent 1,034,290. The keys 19 for the vertical edges of the door are then passed into 60 engagement with the channels formed thereon, the keys being inserted from the bottom of the door, at which point the clearance for the folding dies is formed. The faces of the door are now united, with the panel 65 apertures in register. The uppermost stiff-

ening spacer bar 25 is now placed in position by passing it up sidewise between the recurved marginal edges 21 at the panel aperture and then drawing it down into the position shown. Any suitable means may be employed for this purpose, e. g., a wire welded at one end to the bar and cut off after the latter has been drawn down into position. The bar 25 is then secured by welding the joint between the same and the bottoms of the channels 21. The molding 23 is then placed in position, the panel 15 inserted and the retaining molding 26 screwed into position. The second spacing bar 25 is then passed up from the aperture for panel 16 and welded in position, thus completing the upper portion of the door. The lower portion is in large part a repetition of the upper part, and no difficulty will be found in understanding its assembly from the preceding description.

A door thus constructed presents the great advantage over a door assembled from independent stiles and rail members, that the welding of all joints between the parts 90 may be accomplished from the interior of the door, thus presenting an exterior free from the blemishes or blisters which inevitably accompany a welded joint. Further it presents great advantages over a door with depressed panels in that it permits of a variety of design and artisticity of moldings which are wholly beyond the range of practicability for doors of the pressed panel type.

Obviously the particular moldings and closures may be varied in many ways. Thus in Fig. 3 I have shown the bottom edges of the faces A and B carried down perfectly straight and the opening closed by the insertion of a flanged stiffening bar 42 which is welded in position. In Fig. 4 I have shown a modified form for the edges of the top cross rail and stiles. The edges of the latter are folded to form parallel oppositely faced channels 43 and 44, in one pair of which engage the edges of a flanged stiffening bar 45 and in the other pair an oppositely faced stiffening bar 46. In Fig. 5 the panel is supported directly by the stiffening bar 47 and moldings 48 are arranged on each side of the panel to give a finish to the joint. In Fig. 6 the panel supporting molding 49 is provided with upturned edges 50 which engage in the channels 31 at the 110 lower edge of the panel aperture, together with the flanges of the stiffening bar 51. The latter in turn may be reinforced by a second stiffening bar 52 oppositely faced.

Should it be desired to use two part panels 125 i. e., one for each face of the door as in Fig. 7, to have a space between for filling material of any sort, the supporting moldings may be dispensed with, and the upper edge and sides of the panel, be engaged in the 130

channels 30, while the bottom edge engages in the channels 37 of the stiffening bar 36. Or as in Fig. 8, the lower edge of the panel may be recurved to engage in the channel 31 with the flanges of the stiffening bar 51. Various other modifications will readily suggest themselves.

I claim as my invention:—

1. A metallic structure of the type described comprising front and back face sheets having rail and stile portions, and having registering perforations to receive an inserted panel, spacing closure means at certain of the margins of the sheets, panel supporting means at one edge of the panel aperture insertible between the sheets from an open edge of the door and spacing closure means for closing said open edge after the panel supporting means have been assembled in position.

2. A metallic structure of the character described comprising front and back face sheets having rail and stile portions and having registering perforations to receive an inserted panel section, the margin of said panel perforation being folded and recurved on certain sides to form parallel oppositely faced channels, and one margin of said panel aperture being folded in only one direction, for the purpose described.

3. A metallic structure of the character described comprising front and back face sheets having rail and stile portions and having registering perforations to receive an inserted panel section, the margin of

said panel perforation being folded and re-curved on certain sides to form parallel oppositely faced channels, and one margin of said panel aperture being folded in only one direction, together with panel molding 40 engaging in the channels facing the channel aperture, and stiffening bars engaging in the oppositely faced channels, substantially as described.

4. A metallic structure of the type described, 45 having front and back face sheets, each comprising rail and stile portions, the top and side margins of the sheets being folded at right angles and their edges recurved inwardly to form open channels, the bottoms of which unite to form an edge closure for the structure, stiffening bars engaging the opposed faces of the door and having their edges angled into locking engagement with said marginal channels of the front 55 and back face sheets, in combination with means insertible at the remaining edge of the structure after the other edges are closed, spacing said edges apart but forming an edge closure, all the edges of said structure being continuous and free from apertures, fill pieces or the like, substantially as described.

In testimony whereof I have signed my name to this specification, in the presence of 65 two subscribing witnesses.

HAROLD F. PARISH.
